UNITED STATES PATENT OFFICE.

WILLIAM A. LORENZ, OF HARTFORD, CONNECTICUT, ASSIGNOR TO UNION PAPER BAG MACHINE COMPANY, OF PHILADELPHIA, PENNSYLVANIA, A CORPORATION OF PENNSYLVANIA.

PAPER-BAG MACHINE.

No. 847,957.

Specification of Letters Patent.

Patented March 19, 1907.

Application filed September 29, 1900. Serial No. 31,487.

To all whom it may concern.

Be it known that I, WILLIAM A. LORENZ, a citizen of the United States, residing at Hartford, in the county of Hartford and State of Connecticut, have invented certain new and useful Improvements in Paper-Bag Machines, of which the following is a full, clear, and exact specification.

This invention relates to paper-bag machines, and particularly to that class thereof which are employed for manufacturing square-bottomed paper bags from tucked or bellows-sided tubing.

The invention comprises what is technically known as the "diamond-folding" section of a paper-bag machine, which receives the bellows-sided blanks from any suitable blank-folding mechanism, makes the well-known diamond folds therein, and passes the diamond-folded blank on to any suitable flap-folding mechanism for completing the bag.

The general object of the present invention is to provide an improved construction, arrangement, and mode of operation of the blank-folding mechanism, whereby the unfolding of the bellows-sided tucks and their refolding into the inner triangular folds and the diamond-folding, which are characteristic of this type of bag, are accomplished in a more natural, certain, rapid, and accurate manner than heretofore.

In this invention the paper-bag blanks are carried forward by a rotary or oscillatory blank-support, which provides a folding-bed for supporting the blank during the folding operation. The devices which engage the upper ply of the blank to fold it back during its conversion into a diamond-folded blank are mounted both for sliding and oscillatory movement, whereby the instrumentalities which engage with that upper ply may be advanced in the direction of the travel of the blank during a considerable portion of that travel and may also follow either closely or approximately, as may be desired, the curvature of the path in which the blank is carried. These sliding and oscillatory movements of the said devices are both controlled from and operated through a fixed axis by means of gears or equivalent devices, thus making a simple, compact, easily-observed, and readily-controlled mechanism.

In the drawings accompanying this invention, and in which similar characters denote similar parts, Figure 1 is a front view of my improved machine. Fig. 2 is a side view of the same looking from the left of Fig. 1. Fig. 3 is a vertical section on line 3-3, Fig. 1. Fig. 4 illustrates the blank-folding member and the carrier on an enlarged scale and in a position where the end of the tube is partly opened to assume the box form. Fig. 5 is a view similar to Fig. 4, showing the blank-folding carrier in position after the diamond has been completed and flattened. Fig. 6 represents an end view of the partly-opened-out end of the tube, corresponding with Fig. 4. Fig. 7 is a face view of the diamond, corresponding to the form obtained in Fig. 5; and Fig. 8 shows a modification of the machine, the carrier here shown being of the oscillatory type.

In the drawings, 10 designates the bed-plate, having secured thereto a pair of upright side frames 11 12, in which the several coöperating shafts for driving the various devices are supported. Suitable means are provided for feeding individual blanks or bellows-sided tubing into the machine, these means consisting in the present instance of feed-rollers 13 and 14, mounted on shafts 15 and 16, respectively, the latter being journaled in boxes 17, movably held in the side frames and acted upon by springs 17'. The feed-rollers may be caused to move peripherally in unison by means of gears 18 and 19, mounted on said shafts and driven by a gear 20, mounted on the lower roll-shaft 15 and obtaining motion from a similar gear 21, mounted upon a shaft 22, which constitutes the main driving-shaft of the machine and to which power may be applied from any ordinary source. From the feed-rollers the blank is conducted to a suitable carrier, serving as a support for the blank during the diamond-forming operation. Connected for coöperation with the carrier is a blank-folding member adapted for engaging the upper ply of the tube or blank, while the carrier is provided with means whereby the lower ply of the blank is securely held in place thereon, both carrier and blank-folding member co-acting to open out the end of the blank and to form the diamond, as will hereinafter appear. In the preferred form thereof shown

the carrier is of the rotary type and consists, substantially, of a cylinder, such as 23, mounted upon a shaft 24, which receives rotary movement through a gear 25, secured there-
5 to and in engagement with a gear 26, mounted upon the main driving-shaft 22, above mentioned. The means for holding the lower ply of the tube on the carrier consists, preferably, of a pair of tuck-holders 27, jour-
10 naled at 28 on the carrier and having roll-
receiving portions 29, on which cam-rollers 30 are journaled. These cam-rollers are adapt-
ed to travel around the periphery of suitable
15 cams 31, which are preferably stationary
and which cause the tuck-holders to grip the
lower ply of the blank on both sides simul-
taneously and at the proper time. The car-
rier 23 is also provided with a device for
20 gripping or holding the front end of the lower
ply of the tube or blank, this device being
shown herein as a front diamond-holder 32,
journaled at 33 in the web of the carrier and
carrying a roll 34, in engagement with a suit-
able stationary cam 35, whereby as the car-
rier rotates said holder 32 will be caused to
25 release the blank at a certain time, while a
spring 36 may be employed for closing said
holder over the lower ply of the blank, as
shown in Fig. 3.

30 The blank-folding member, which, as
above stated, is connected for coöperation
with the carrier, is herein illustrated as a re-
ciprocative plate adapted for oscillation
35 around a fixed axis and one edge of which
serves as the bottom-defining edge for the
blank. Means are provided for actuating
the blank-folding member, or, as it is gen-
erally called, the "defining-plate," in such a
40 manner as to cause the defining edge to
maintain a substantial distance from the
surface of the carrier during the diamond-
forming operation. This result is accom-
plished in the present instance by recipro-
45 cating the defining-plate in a guide, which in
turn is mounted for oscillation around an
axis, both movements—reciprocation and
oscillation—being so timed for coaction with
each other as to cause the defining edge to
50 travel in a path indicated by dot-and-dash
line P. (See Figs. 4 and 5.) I have shown a
folding member and a carrier both of which
are movable, so that the defining edge will be
caused to travel in unison with the carrier
55 and at a substantial distance from the sur-
face thereof during the formation of the dia-
mond, and particularly during the defining of
the inner triangular folds thereof. The blank-
folding member or defining-plate consists,
60 substantially, of a plate 37, having a defining
edge 38 and adapted for reciprocation within
a guide 39, the plate being provided with
rack-teeth 40, in engagement with a pinion 41,
which is loosely mounted upon a spindle 42.
65 Proper oscillatory movement may be im-
parted to the pinion 41 by a sector 43, se-

cured to a spindle 44, which is journaled in a
bracket 45, held on a cross-bar 46, whereby
the side frames 11 and 12 are tied at their
tops. The spindle 44 also carries at its outer
70 end a crank-arm 47, to which a proper oscil-
latory movement may be imparted by a cam
48, mounted upon the main shaft 22 and hav-
ing a groove in engagement with a roller 49,
which is journaled on a lever 50. The rear
75 end of said lever 50 is fulcrumed at 51 on a
bracket 52, while its forward end is connect-
ed by a link 53 with the above-mentioned
crank-arm 47. While the plate 37 may be
80 reciprocated in the guide 39 by the means
just described, oscillatory movement may be
imparted to said guide around an axis in
alinement with the spindle 42, the guide 39
being provided with gear-teeth 54, in engage-
85 ment with a sector 55, mounted upon a spin-
dle 56, which is journaled in a bracket 57 and
carries at its outer end a crank-arm 58. This
88 arm 58, and consequently the spindle 56,
may be oscillated by a suitable cam 59, the
groove of which is in engagement with a
roller 60, journaled on a lever 61, having its
90 fulcrum on the spindle 51 and the free end of
which is connected with the crank-arm 58 by
a link 62. From the foregoing description it
will be clearly understood that the position
95 of the defining edge may be absolutely and
positively controlled according to the shapes
of the operating-cams 48 and 59, each of
which is in the present instance made in
halves, so as to be readily removable from
100 the main shaft to permit the substitution of
other cams therefor.

The folding-plate 37 carries near the de-
fining edge a pair of box-holders 63, which
are pivoted at 64 to bracket 65, secured to or
forming a part of the plate 37. These box-
105 holders 63 are actuated to close against and
hold the upper ply of the tucked tube or
blank—as, for instance, by springs 66—
while abutments 67, secured to the brackets
45 and 57, respectively, may serve to open
110 said box-holders against the action of said
springs 66 when the defining-plate is in its
blank-receiving position. (Shown in Fig. 3.)
When the plate 37 arrives at its blank-dis-
charging position, the box-holders may be
115 again opened by abutments 68, secured to
the side frames 11 and 12.

After passing the feed-rolls 13 and 14 the
blank is properly guided by a guide-plate 69
between the blank-folding member and the
carrier and into position to be gripped by the
tuck-holders 27 and the box-holders 63.

Secured to the side frame 12 is a stud 70,
on which is journaled a lever 71, carrying at
one end a drop-plate 72, adapted to coöper-
120 ate with the carrier in flattening and com-
pleting the diamond after the tuck-holders
and box-holders have stretched out the sides
of the tucked tube. The lever 71 may be
125 actuated by a cam 73, secured to a shaft 74
130

and engaging a cam-roller 75, journaled on the arm 71, while a spring 76 may be employed to force the drop-plate 72 against the carrier. After the diamond has been flattened by the drop-plate the blank may be carried into contact with a presser-roll 77, mounted upon the shaft 74, after which a delivery-plate 78 may deflect the blank from the carrier and conduct the same to other devices, which may include a paster-roll and flap-folding devices 79 and 80, whereby the blank is transformed into the completed bag. The presser-roll shaft 74, which also carries the cam 73 for actuating the drop-plate, obtains rotary movement through a gear 81, engaged by a gear 82, which is secured upon the carrier-shaft 24 and which through an intermediate 83 also drives the flap-folding devices, said intermediate being in engagement with a gear 84. (Shown in dot-and-dash line in Fig. 1.)

In Fig. 8 I have shown a modification of my improved machine, which in this instance includes an oscillatory carrier instead of a rotary device, as described. Here the carrier 100 is provided with gear-teeth 101, in engagement with a sector 102, to which proper movement may be imparted by a cam 103, engaging the cam-roller 104, journaled on the arm of the sector 102, the latter being pivoted at 105 to the bracket 52.

The operation of my improved machine is as follows: Bellows-sided or tucked tubing is introduced into the machine by the feed-rolls 13 and 14 and guided by the plate 69 between the blank-folding member 37 and the carrier 23 in such a manner that the tuck-holders 27 and the front diamond-holder 32 will engage the lower ply of the blank, as seen in Fig. 3, and it will thus be carried along by the carrier in the direction of arrow *a*. While the blank is delivered to the tuck-holders the box-holders 63 of the blank-folding member 37 are open, and the movement of the blank-folding member with the box-holders is so timed relatively to the carrier that the front edges of the tuck-holders and of the box-holders will be in alinement when they grip the blank, after which both the carrier and the defining edge of the blank-folding member will travel in unison during the formation of the diamond. The path which the defining edge traverses in its course is, as has been stated, subject to variation by the substitution of the required cams in lieu of the cams 48 and 59 shown in the drawings. In Figs. 4 and 6 the end of the tucked tube is shown opened out into what is generally known as the "box form," clearly illustrating the manner of forming the inside triangular folds, and in Figs. 5 and 8 the blank-folding member is shown as having arrived at the end of its stroke and showing the drop-plate in its

operative position substantially completing the diamond. At this time the box-holders are disengaged from the blank and the latter is drawn forward under the drop-plate 72, which can now move more closely toward the carrier and the defining-plate and will therefore flatten the diamond more fully. Just as soon as the drop-plate compresses the blank against the defining-plate after the latter has arrived in the position shown in Fig. 5, in which, as has previously been mentioned, the box-holders are open, the defining-plate may start on its return stroke and withdraw from under the folding-plate. It will be evident from the description given above that when the defining-plate starts on its return stroke the box-holders will close after the rear flap of the diamond has been withdrawn sufficiently to clear them. Hence the blank-folding member may start on its return stroke immediately after the drop-plate has arrived in its operating position, and thus obviate all loss of time. As the blank is withdrawn from under the drop-plate 72 it is passed under the roll 77 by the front diamond-holder and the tuck-holders, which will after they pass the roll release the blank. The latter is then delivered to the flap-folding devices carried by rollers, (indicated by dot-and-dash lines 79 and 80.)

It is evident that many changes may be made in the particular construction of some of the elements of my improved machine without departing from the gist of my invention, and while I have shown and described the blank-folding member in co-operative connection with a rotary blank-carrier it should be understood that any other form of carrier may be successfully employed in connection with the blank-folding member and its operating mechanism whereby a substantial separation of the tucked sides of the tube adjacent to the defining edge is maintained during the formation of the inner triangular fold of the diamond.

In my copending application, Serial No. 32,123, filed October 5, 1900, I have shown, described, and claimed mechanism broadly similar to that shown in this application, in that it embodies the combination, in a movable blank-support, of an oscillatory blank-folding member having a defining edge, means for pivotally supporting said member on an axis remote from said edge, means for causing the advance movement of the entire blank-folding member, and means independent of and extraneous to the blank-support for oscillating the said member in its support. My present application so far as it shows and relates to such devices does so for the purpose of claiming specific novel constructions and combinations thereof and is a subordinate application to that above mentioned in respect of the said devices.

Having described my invention, what I claim as new, and desire to secure by Letters Patent, is—

1. The combination with a blank-support, of a supporting-guide mounted on a fixed axis adjacent to the blank-support, a blank-folding member mounted for sliding movement in the said guide, means independent of the blank-support for swinging the guide and sliding the blank-folding member in the guide in coactive relation to the blank-support, and means coacting with the blank-folding member to cause the upper ply of the blank to turn therewith. 70
2. The combination with a blank-support, of a supporting-guide mounted to swing on a fixed axis adjacent to the blank-support, a blank-folding member having a defining edge and mounted for sliding movement in the said guide, means independent of the blank-support for swinging the guide and sliding the blank-folding member in the guide to carry the said defining edge in coactive relation to the blank-support, and means, coacting with the blank-folding member, to cause the upper ply of the blank to turn therewith. 75
3. The combination with a blank-support, of a blank-folding member, provided with means for turning back the upper ply of a blank carried by the support, a guide mounted to swing on a fixed axis and supporting the said folding member for sliding movement, and means including toothed gearing concentric with the said axis for swinging the guide and for sliding the folding member in the guide. 80
4. The combination with a rotary blank-carrier, having tuck-holders cooperative therewith, of a slideable reciprocatory blank-folding member, box-holders cooperative therewith, means independent of the blank-support for oscillating the blank-folding member during its operating movement, and means for opening and closing the box-holders to grip and release the blank. 85
5. The combination with a rotary blank-support having tuck-holders cooperative therewith, of a blank-folding member mounted for sliding and oscillatory movements relative to a fixed axis and including box-holders, means including toothed gearing mounted eccentric with the said axis for effecting the said sliding and oscillatory movements, and means for opening and closing the box-holders to grip and release the blank. 90
6. The combination with a traveling blank-support, of a blank-folding member provided with means for turning back the upper ply of the blank, a guide mounted for swinging movement and supporting the said folding member for sliding movement, means for swinging the guide, and means including toothed gearing for sliding the folding member in the guide. 95
7. The combination of a traveling blank-support, of a blank-folding member provided with means for turning back the upper ply of a blank carried on the said support, a guide mounted for turning movement and supporting the said folding member for sliding movement, means for swinging the guide, and means including a gear mounted in substantially concentric relation with the axis of the swinging guide for sliding the folding member in coactive relation to the blank-support. 100
8. The combination with a traveling blank-support, of a blank-folding member having means, including a defining edge, for turning back the upper ply of a blank carried by the said support, a guide mounted for oscillation and supporting the folding member for sliding movement, means for oscillating the guide, gear-teeth appurtenant to the folding member, a driving-gear meshing with said teeth and mounted to turn in concentric relation to the axis of oscillation of the guide, and means for moving the said gearing to carry the said folding member in coactive relation with the blank-support. 105
9. The combination with a traveling blank-support, of a blank-folding plate, having means, including a defining edge, for turning back the upper ply of a blank carried by the said support, a guide mounted for oscillation and supporting the said folding-plate for sliding movement, toothed gearing for swinging the said guide including a gear mounted in concentric relation to the said guide, and means for sliding the folding member in the guide, including gear-teeth appurtenant to the said plate, and including a gear mounted in concentric relation with the first-named gear and with the axis of oscillation of the guide. 110
10. The combination with a rotary blank-support, of a blank-folding member provided with means, including a defining edge, for turning back the upper ply of a blank carried by the said support, a guide mounted for swinging movement adjacent to the said support, and supporting the said folding member for sliding movement, and means for swinging the guide and sliding the plate therein to carry the said defining edge in coactive relation to the blank-support and at a substantial distance therefrom during the folding movement. 115
11. The combination with a rotary blank-support, of a folding member, provided with means including a defining edge for turning back the upper ply of a blank carried by the said support, a guide mounted for swinging movement, and supporting the said folding member for sliding movement, means including toothed gearing for sliding the folding member in the said guide, and means including toothed gearing for swinging the said guide in cooperation with the said sliding movement to carry the said defining edge forward in coactive relation to the blank- 120
12. The combination with a rotary blank-support, of a blank-folding member provided with means, including a defining edge, for turning back the upper ply of a blank carried by the said support, a guide mounted for oscillating movement, and supporting the said folding member for sliding movement, means including toothed gearing for oscillating the guide, and means including toothed gearing for carrying the said folding member in coactive relation to the blank-support. 125
13. The combination with a traveling blank-support, of a blank-folding member provided with means, including a defining edge, for turning back the upper ply of a blank carried by the said support, a guide mounted for oscillating movement, and supporting the said folding member for sliding movement, means including toothed gearing for carrying the said folding member in coactive relation to the blank-support. 130

support and at a substantial distance therefrom during the folding operation.

12. The combination with a rotary blank-support having tuck-holders, of a folding-plate having a defining edge and box-holders, a guide mounted for swinging movement and supporting the said folding member for sliding movement, gear-teeth appurtenant to the said folding member and to the said guide, and toothed gearing, including gears mounted in concentric relation to the axis of rotation of the guide for swinging the guide and for sliding the folding member in the guide.

13. The combination with a rotary blank-support, of means for turning back the upper 15 ply of a blank carried by the support to form diamond folds therein, including a folding member having a defining edge mounted for sliding and oscillatory movements, means including toothed gearing for effecting the said oscillatory and sliding movements and cooperating to advance the said folding member in the direction of travel of the blank.

14. The combination with a rotary blank-support, of means for turning back the upper 25 ply of a blank carried by the support, including a folding member having a defining edge and mounted for swinging and sliding movements, operating means including 30 toothed gearing for swinging said folding member, operating means including toothed gearing for sliding said member, the two said operating means coacting to advance the said folding member in the general direction 35 of travel of the blank, and to carry the defining edge of said member in a path which

diverges from the path of travel of the blank during the operation of turning back the said 40 ply.

15. The combination with a rotary blank-support, of means for turning back the upper 45 ply of a blank carried by the support, including a folding member having a defining edge and mounted for sliding and oscillatory movements, operating means including 50 toothed gearing for effecting the said oscillatory movement, and operating means including a rack and pinion for effecting the said sliding movement, the two said operating means coacting to advance the said folding 55 member in the general direction of travel of the blank during the folding-back operation.

16. The combination with a rotary blank-support, of means for turning back the upper 55 ply of a blank carried by the support, including a folding member having a defining edge, a swinging guide in which the said folding member is mounted for sliding movement, operating means including toothed gearing for swinging the said guide, and operating 60 means including a rack and pinion for sliding the said folding member in the guide, the two said operating means coacting to advance the blank-folding member in the general direction of travel of the blank and to carry the 65 defining edge of the said folding member in a variant path relative to the rotary path of the blank-support.

WILLIAM A. LORENZ.
